DEVICE TO RESTORE FORCIBLY INTERFERINGLY OPERATED TYPE CARRIERS

Filed Dec. 12, 1950

UNITED STATES PATENT OFFICE

2,612,253

DEVICE TO RESTORE FORCIBLY INTERFERINGLY OPERATED TYPE CARRIERS

William F. Helmond, Clinton, Conn., assignor to
Underwood Corporation, New York, N. Y., a corporation of Delaware

Application December 12, 1950, Serial No. 200,461

2 Claims. (Cl. 197—27)

1

This invention relates to typewriting machines and more particularly to devices for forcibly restoring type actions which due to too closely successive operations have interfered and have become tied up against free spring urged return. The invention, as will be noted later, relates also to margin release mechanism for conditioning the machine to pass normal writing margins predetermined by a margin stop mechanism.

Devices to restore type actions forcibly are known in the art, and heretofore have included an operating control which is additional to the conventional other operating controls in the machine.

According to the present invention it has been conceived to operate the margin release mechanism and the type action restoring mechanism by a common control or key, the object being to hold the number of keys in the keyboard to a minimum, thereby not only to hold the cost of the machine down, but more importantly to simplify the control movements for tending the machine.

It is another object to provide efficient and simple mechanism for conveniently and forcibly restoring tied up type action.

Referring now to the drawings,

Figure 1 is a fragmentary sectional side elevation of a typewriting machine embodying the invention, the section being taken substantially along line 1—1 of Figure 2.

Figure 2 is a front view of certain parts of the machine seen in Figure 1.

The main frame of the machine comprises two spaced side walls 10 connected by a track structure 11 upon which a carriage 12 for support of a work sheet is guided. The carriage includes a grooved rail 13 which is associated with the track structure 11 by means of anti-friction elements 14. End plates 15 rising from said rail 13 support a conventional platen roll 16. At the rear of the carriage there extends parallel thereto between the end plates a rod 17 whereon there are carried a left and a right margin stop, respectively numbered 18 and 19.

The machine comprises a system of type actions such as fully disclosed in the patent to Helmond, No. 2,072,878, dated March 9, 1937. Said type actions include each a type bar, and one such type bar, at the middle of the system, is shown in Figure 1 and numbered 20. The type bars 20 of the system comprise an array which is arcuate as viewed from the front of the machine, and the individual type bars are swingable toward a common printing point on the platen about a pivot

wire 21 which is symmetrically arcuate with reference to the stated arcuate type bar system. All type bars 20 in the final printing approach toward the platen enter a usual type guide 22 and are accurately guided thereby.

The various type actions include each a sublever 23 and the latter are accommodated, transversely spaced in the machine, on a pivot wire 24. Referring particularly also to Figure 2, the various levers 23 are upreaching from the pivot wire 24 to graded extents, for wire links 25 to connect the upper ends of the levers operatively similarly to the related type bars 20. By means not shown, but fully disclosed in said patent, type keys 26 provided in the keyboard of the machine are in operative control of said levers 23 to swing them in a direction away from the platen to thereby actuate the type bars 20 for printing. Springs 27 individual to said levers 23 serve to return the type actions individually to their normal rest positions wherein all the type bars 20 extend horizontally from the pivot wire 21.

The carriage 12 is under control of a usual letter feed escapement, not shown, which allows stepwise turning of a pinion 28 meshing with a rack 29 on the carriage.

The margin controlling mechanism, additional to the left and right margin stops 18, 19, includes a counterstop in the form of an arm 30 which reaches upwardly through a perforation 31 in a top plate 32 of a usual housing. Said counterstop arm 30 has at its lower end a vertical slot 35, see Figure 2. Into this slot reaches a pin 36 which is fast on a bracket 37, the latter carried fast on a crossbar 38 of the machine. Said counterstop arm 30, under the urge of a spring 40, is normally held elevated to the limit provided by the lower end of the slot 35 abutting upwardly against said pin 36. Said spring 40 moreover urges the arm 30 to swing to the right limit in said perforation 31. At the end of each carriage return the margin stop 18 limitedly engages the upper end of the counterstop arm 30. On the other hand, the carriage in traveling leftwardly during typing finally causes the line end margin stop 19 to encounter and swing the counterstop arm 30 to the left in said perforation 31. Such swinging of the arm 30 results in operation of a lever 41 to swing a front end 42 thereof out of registering relation with a clearance notch 43 provided in a usual type bar actuatable universal bar 44. The lever front end 42 then blocks the universal bar 44 against escapement actuating operation and this in turn blocks the type bars 20 against printing operation. Either of the

stated margin limits may be passed by operation of a margin release mechanism which lowers the counterstop arm 30 below the range of the margin stops 18, 18. This margin release mechanism comprises a lever 45 having a forwardly reaching arm 46 bearing a key 47, and comprising also a rearwardly reaching arm 48, the lever being pivoted intermediate the arms 46, 48 at 50. A spring 51 urges the lever to occupy normally the position seen in Figure 1. The rear end of the lever arm 48 underlies the right end of a crosswise extending lever 52. The latter is pivoted intermediate its ends on a rigid bracket 53 and has at the left end a pin-and-fork connection 54 with the lower end of the margin stop arm 30. It follows therefore that if it is desired to return the carriage beyond the normal limit provided by the margin stop 18, or when it is desired to continue to type when the position defined by the line end margin stop 19 is reached, this can be done by operation of the key 47, which causes the counterstop arm 30 to be lowered below the range of the margin stops 18, 19.

At the front of the sub-levers 23 of the various type actions there is provided a bail 60 which extends transversely of the machine and comprises laterally spaced upright arms 61 and a downwardly arced bridging member 62. The arc of the bridging member 62 is formed for contact with the various sub-levers 23 near their upper ends. Short studs 63 reaching inwardly from the opposite side walls 10 of the machine give pivotal support to said bail at the lower ends of its arms 61.

Whenever the type bars 20, by interfering with each other, as indicated in Figure 1 in a dot-and-dash showing, become tied against free return, the bail 60 is operated towards the rear of the machine to force the unrestored sub-levers 23 to their rearward, normal positions.

The means for rearwardly operating the bail includes the key-bearing lever 46 which also serves to release the aforesaid margin mechanism. For operating said bail 60 the lever arm 46 has a link 64 which is operatively connected to a bell crank 65 having an upreaching arm 66 which by means of a pin-and-slot connection 67 is communicative with the right bail arm 61. The bell crank is fast on a cross shaft 68 which is pivotally borne in the frame ends 10 of the machine. At the left end of the shaft 68 there rises an arm 69 similar to the arm 66, having a pin-and-slot connection 67 with the left bail arm 61. The structure comprising the shaft 68 and the arms 66, 69 cooperates with the relatively frail bail 60 to cause its opposite ends to move in unison.

The axis for the bail 60 as afforded by the studs 63 lies closely in front of the pivot rod for the various sub-levers 23. It has been infeasible to provide a shaft connection directly between the arms 61 of the bail because the various key levers in the machine take up the space for this.

It is to be observed that at operation of the key 47 for margin releasing action, the bail 60 operates idly in free space inasmuch as all the type actions are then in their restored, rearward positions. On the other hand, whenever the key 47 is operated for returning type actions, the counterstop 30 is lowered idly without causing any difficulties whatever. This compatibility for operation by the same key of totally unrelated mechanisms had to be recognized and such recognition constituted a vital step in arriving at the aforesaid invention.

While only one embodiment of the invention has been shown and described, many variations may be resorted to within the scope of the invention, and portions of improvements may be used without others.

What is claimed is:

1. In a typewriting machine having a frame, a letter feeding carriage, and spring-restored individually operable type actions which if operated in too close succession will by interference bind against each other and fail to restore; an element on the frame and an element on the carriage normally in cooperative margin controlling range with each other, a bail extending transversely of the machine and normally clear of the operating paths of said type actions but operable to restore forcibly any type action failing to restore, a key lever extending fore-and-aft in the machine and comprising a rearwardly reaching arm and also a forwardly reaching key-bearing arm connected to said bail to operate the latter, and means operated by said rearwardly reaching arm to move said elements relatively out of cooperative margin controlling range.

2. In a typewriting machine having spring-restored individually operable type actions which if operated in too close succession will by interference bind against each other and fail to restore; a transversely extending restoring bail for said type actions normally out of their operating paths and comprising laterally spaced arms swingably supported in the machine and a bridging member extending intermediate the swinging ends of said arms, a transverse shaft pivotally supported in the machine and having arms fast at its opposite ends operatively connected to the spaced arms of said restoring bail to cause them to swing in unison, and means, including an operating key, to rock said shaft for operation of said bail in unison at both ends to restore type actions that have failed to restore.
